UNITED STATES PATENT OFFICE

116,387

DESIGN FOR A TEXTILE FABRIC OR SIMILAR ARTICLE

Mark Sigoda, Laurelton, Long Island, N. Y.

Application May 3, 1939, Serial No. 84,777

Term of patent 3½ years

To all whom it may concern:

Be it known that I, Mark Sigoda, a citizen of the United States, residing at Laurelton, Long Island, in the county of Nassau and the State of New York, have invented a new, original, and ornamental Design for a Textile Fabric or Similar Article, of which the following is a specification, reference being had to the accompanying drawing, forming part thereof.

The figure of the drawing is a plan view of the textile fabric showing my design.

The dominant feature of my design comprises the base fabric upon which spaced narrow ribbons, each having closely arranged ruffles or folds formed therein, are applied and secured in the ornamental arrangement shown in the drawing.

I claim:

The ornamental design for a textile fabric or similar article, substantially as shown and described.

MARK SIGODA.
